FADING ELIMINATION

Harold H. Beverage and Harold O. Peterson,
Riverhead, N. Y., assignors to Radio Corpora-
tion of America, a corporation of Delaware

Original application March 15, 1928, Serial No.
261,738. Divided and this application February
10, 1936, Serial No. 63,132

12 Claims. (Cl. 250—2)

The invention relates to the elimination of what is commonly known as fading in wireless or radio signalling. It is particularly adapted for use in the reception and transmission of short wave signals, especially in locations where fading conditions are particularly troublesome.

This application is a division of our copending application, Serial No. 261,738, which was filed on March 15, 1928.

We have found that signals picked up on antennae located at different points have different fading characteristics, and that where short wave antennae are located at separated points that the signals might be of a maximum intensity at any particular instant on an antenna located at one point and at the same instant be of a minimum intensity on an antenna located at another point. In order to combine the signals received on the various antennae which are, as above stated, geographically separated with respect to each other, the first thought was to carry the radio frequency energy picked up on the various antenna systems in question to some common receiver and to add the separate energies directly together at the common combining point. This, however, has its limitations because it has been found that the phase relationship between the signal voltage received at one antenna and the signal voltage received upon another antenna geographically separated from the first antenna does not remain fixed but changes from moment to moment. Therefore, it is relatively ineffectual to provide an arrangement for directly combining the radio frequency voltage from the plurality of antenna systems located at various geographically separated points since these voltages might add at one instant and subtract at another instant, due to the fact that the radio frequency voltages from the various antennae will not always be in phase.

It is, therefore, an object of our invention to provide a method and means of combining signals from various geographically separated antennae independent of the phase relationship of the signals as received on the various antennae. The broad idea of combining signals from various geographically separated antennae has been disclosed in our U. S. Patent 1,819,589, issued August 18, 1931.

Referring to the accompanying drawing, Fig. 1 illustrates an arrangement for combining signals in a receiving circuit independently of their relative phase; and

Fig. 2 illustrates a modification of Fig. 1.

In Fig. 1 we have shown a method for elimi-

nating short wave fading in which the audio frequency outputs of two geographically separated radio receiving systems are added. Radio frequency energy of the desired signal is picked up on two geographically separated antenna systems, 1 and 3, which carry their respective energies to receiving systems of any desired character 5 and 7. Associated with the receiving systems 5 and 7 are two separate local oscillators 9 and 11, there being one oscillator for each receiver system. These oscillators are used to heterodyne the incoming signal energy as received upon the geographically spaced antennae 1 and 3. In each receiving system 5 and 7, which are intended to include the usual detector circuits, 13 and 15, the outputs of the detectors are fed through any desired form of leads to amplifiers 13 and 15. The outputs of amplifiers 13 and 15 are impressed upon the primary windings 19 and 21 of the transformer 17 from which the energy is transferred to the secondary winding 23. Included in the secondary circuit 23 are a set of phones or any other type of receiving unit or translating device 25.

It will be noted from the above that there is one primary winding 19 or 21 for each receiving system 1 or 3 and that the secondary winding 23 of the transformer 17 contains two different frequencies from the two different receiving systems. The heterodyne oscillator 9 which is coupled with receiving system 5 is preferably so adjusted that the beat note resulting may be of the order of 800 cycles. The oscillator 11 which is coupled with the receiving system 7 is preferably so adjusted that the beat note resulting may be of a frequency of 1,000 cycles, although it is to be understood that we can successfully use beat frequencies other than those which we have mentioned. It is thus seen that there is an 800 cycle output from receiving system 5 and a 1,000 cycle output from receiving system 7. These two frequencies which will now be denoted by "F₁" and "F₂", respectively, are passed through the two primary windings 19 and 21 respectively of the output transformer 17 and both frequencies appear in the secondary winding 23 which is connected with the receiving instrumentality such as the phones 25.

If an operator is listening in the phone 25, he may note that in one instant the 800 cycle note or frequency "F₁" at one time predominates, due to the fact that the energy picked up by the antenna system 1 which is connected to this receiver is greater than the energy picked up by the antenna system 3 connected with receiving

system 7. However, at another instant it might appear to be that the 1,000 cycle note, or frequency "F₂" will predominate in the phone 25, due to the fact that the energy picked up by the 5 second antenna system 3 is now greater than that picked up by the antenna system 1 of the first receiver 5.

It is thus seen that there are two different frequencies in the secondary of the transformer 17 and they can not oppose each other for any appreciable length of time. However, if the same frequencies are in phase their energies will add, but when they get out of phase, their energies will subtract, and in this case it is quite obvious 15 how it is possible to have periods of long duration when the signal intensity is very great due to the fact that these two same frequencies add and again there are periods when there are very feeble signals due to the fact that these same frequencies oppose each other. Thus, by using two 20 separate antenna systems and two separate local oscillators as has been above described, to produce two different audio frequency outputs, an arrangement can be established where the audio 25 frequency outputs in an output transformer are arranged to obtain satisfactory reception since one beat note will predominate at one instant and another beat note will predominate at another instant, but at all times when any signals 30 reach antenna 1 or 3 the operator will have a signal in phones 25.

It is thus seen that we have produced by this arrangement a method and apparatus which will effectively eliminate the effect of fading by combining the signals received on each of the two or more geographically separated antenna systems independently of the phase relationship.

From the above description it is obvious that the same method and principle may be used to 40 combine the outputs of more than two antennae. Thus, to combine the outputs from "n" antennae, in accordance with the principle above set forth, "n" receivers would be used and produce "n" different frequency outputs which would all add 45 their energies together in the common receiving instrumentality, as for example, the phones 25.

As also will be understood from a reading of the above description it will be noted that the speed of signalling is practically a function of 50 the frequencies transferred to the receiving instrumentality. Therefore, if it is necessary to increase the speed of signalling to any great extent it is advisable to substitute two low radio frequencies for the frequencies referred to above 55 as F₁ and F₂.

In order to adapt the system shown by Fig. 1 to higher signalling speeds, it is desirable to modify the showing of Fig. 1 to operate with low radio frequencies for F₁ and F₂. Fig. 2 shows a 60 suitable form for such a modification. Referring now to Fig. 2 antennae 31 and 33 are coupled to transmission lines 39 and 41 by suitable means, such as transformers 35 and 37. The transmission lines 39 and 41 terminate at receivers 43 and 65 45 respectively. Each of the receivers 43 and 45 heterodyne the received signal to a lower frequency, either by autodyne reception, or by using separate oscillators 47 and 49. For example, oscillator 49 may be adjusted to produce a beat frequency F₁ of 40,000 cycles, and oscillator 49 may be adjusted to produce a beat frequency F₂ of 42,000 cycles on the same signal.

The outputs of receivers 43 and 45 are connected in a suitable manner to an intermediate 70 frequency amplifier 51, which amplifies F₁ and

F₂ equally, but is selective enough to exclude undesirable frequencies lying outside of the 40,000 to 42,000 cycle band.

Amplifier 51 is connected to the primary 53 of transformer 55. The secondary 57 of this transformer 55 is associated with a full wave rectifier consisting of devices 59 and 61. The rectified current output of the rectifiers 59 and 61 is arranged to operate a recorder or other suitable receiving instrumentality 65. Connected across 10 the output of the rectifier for the purpose of suppressing the beat frequency between F₁ and F₂, while allowing the relatively low frequency keying impulses to pass is a capacity element 63. In the example cited, where F₁ has been chosen, for example, as 40,000 cycles and F₂ as 42,000 cycles, the beat note will be (F₂ - F₁) or 2000 cycles, and with a full wave rectifier, this would largely appear as the second harmonic, or 4000 cycles. The 15 keying pulses have a fundamental frequency of 20 about 40 cycles per second for a Morse code speed of 100 words per minute. Hence it will be seen that the capacity 63 will have 100 times more shunting effect on the combination frequency than on the keying frequency in the example cited. If greater speeds of transmission are desirable, condenser 63 could be replaced by a low 25 pass filter, which would pass high speed keying impulses, but would entirely suppress the combination frequencies. 30

While Fig. 2 and the description pertaining thereto has been illustrated by showing two antennae and assuming a frequency difference of 2000 cycles, it is to be understood that several 35 antennae could be combined by utilizing more receivers and combining the outputs of these receivers in a suitable intermediate frequency amplifier with suitable spacing between the different heterodyne frequencies.

The principles involved in Fig. 2 are fundamentally the same as in Fig. 1, excepting that a receiving instrumentality has been substituted which will be operative over a wider band of frequencies than the phones of Fig. 1. Since the frequencies F₁, F₂, F₃, etc. are different, the phase 45 relations between them change at a very high rate as compared with both the rate of fading and the rate of keying. Therefore, it is possible to suppress the combination frequencies without interfering with the keying pulses, as has already 50 been explained. Hence, it is seen that changes in radio frequency signal phase between the several antennae, have no effect on the final rectified output, and that the energies are added in the recorder irrespective of phase relations. 55

This results in a final signal output relatively free from fading at the receiving instrumentality, provided that the several antennae have been located for suitable fading diversity. We have found that a spacing on the order of 1000 feet 60 between antennae gives excellent diversity on short wave signal fading, for example, on wave lengths up to at least 30 meters.

We claim:

1. The method of receiving wireless signals 65 with geographically spaced antenna systems which comprises receiving the same signal upon each of a pair of geographically separated antenna systems and producing a pair of signal effects therefrom, producing in each of said receiving systems associated with said geographically spaced antenna systems a beat note of different frequency, combining and then rectifying the separate beat notes from each of said antenna systems in a receiving circuit whereby the separate 70 75

signal energies are combined independently of their relative phase relationship and the effects of fading are substantially eliminated.

2. The method of receiving wireless signals with 5 geographically spaced aerials which comprises, receiving the same signal upon each of a pair of geographically separated aerials and associated receiving systems for producing a pair of signal effects therein, introducing separate frequency 10 energy in each of said receiving systems for producing a beat note of different characteristics in each of said receiving systems, combining and then rectifying the said beat notes produced in a combining circuit whereby the signals received 15 upon each of said geographically separated receiving systems may be combined independently of the phase relationship of the signals reaching the same and the effects of fading substantially reduced.
- 20 3. The method of receiving wireless signals with geographically separated aerials which comprises, receiving the same signal upon each of a plurality of geographically separated aerials, and producing a plurality of signal effects there- 25 on directing the energy from each of said aerials to separate receiving systems, introducing into each of said receiving systems a second frequency and producing a beat frequency differing in character in each of said receivers, amplifying the 30 beat frequency produced in each of said systems, combining and then rectifying the separate beat frequencies in a combining circuit whereby the effects of fading are substantially eliminated and the signals received upon each of said aerials are 35 combined independently of the phase relationship.

4. An apparatus for the elimination of fading comprising, a pair of geographically spaced antennae each adapted to receive the same signal 40 effect, a receiving system associated with each said antenna, means for producing beat notes in each of said receiving systems, said beat notes differing in frequency in each of said systems, a combining circuit, a responsive device, and 45 means for so combining and rectifying the beat notes from each of said systems that the received signals as sensed by said responsive device are substantially unaffected by fading and are combined independently of the phase relationship 50 of the signals reaching said antenna.

5. An apparatus for the elimination of fading comprising, a plurality of geographically spaced antenna systems for receiving the same signal effect, a receiving system associated with each 55 of said antennae, an oscillator of different frequency associated with each of said receiving systems, means for producing a beat note by the action of said oscillator frequency upon said received signal frequency, means associated with 60 each of said receiving systems for combining and then amplifying the beat notes so produced, a beat frequency detector responsive to the combined energy from said amplifying means and means associated with said beat frequency de- 65 tector and so characterized that upon operation in response to signals simultaneously received by said plurality of antennae the effects of fading are substantially reduced independently of the phase relationship of the signals reaching said 70 antenna systems.

6. An apparatus for the elimination of fading comprising, a plurality of antennae each having different instantaneous fading characteristics, a separate receiver associated with each of said 75 antennae, means for producing different output

frequencies from said receivers for the same received signals, a common selective intermediate frequency amplifier, a rectifier coupled with the output of said intermediate frequency amplifier, a receiving instrumentality associated with the 5 output circuit of said rectifier and a condenser shunting said output circuit, whereby signals received upon said antennae are received in said receiving instrumentality substantially unaffected by fading and are combined independently of the 10 phase relationship of the signal reaching said antennae.

7. An apparatus for the elimination of fading comprising, a plurality of geographically spaced antennae each having different instantaneous 15 fading characteristics and each adapted to receive the same signal energy, a separate receiver associated with each of said antennae, means for producing a different radio frequency heterodyne beat note on the same signal with each 20 receiver, a selective intermediate frequency amplifier associated with the output of each of said receivers for equally amplifying the separate beat frequencies, a full wave rectifier connected with the output of said amplifier, a filtering means connected in the output circuit of said rectifier, and a receiving instrumentality also associated with said rectifier in the output circuit, whereby signals received upon said geographically spaced antennae have their energies 25 30 added in said receiving instrumentality and are combined irrespective of the phase relationship and the effects of fading are substantially eliminated.

8. A method of reducing fading effects, which 35 comprises receiving radio signaling waves of relatively high frequency at separated places, combining said waves received at said places with combining waves of frequency different from that of the received waves to produce intermediate frequency waves of frequency lower than that of said received waves, the frequency of said combining waves being different at different ones of said places, whereby intermediate frequency waves of different frequency result from 40 said combining actions, adding said waves of intermediate frequency to produce a resultant wave, and detaching the signal component of the latter wave as a relatively low frequency signal 45 current. 50

9. The method of reducing fading effects in the reception of radio signals, which comprises receiving at a plurality of receiving stations radio signals transmitted from the same transmitting station, beating the received signals at each receiving station to an intermediate frequency, the said intermediate frequency being different for different ones of the receiving stations, transmitting the said intermediate frequency currents from each receiving station to a common station 60 and combining and then rectifying at the latter station the said intermediate frequency currents. 55

10. In a radio signaling system, the combination of a plurality of receiving stations, each having means to receive a signal sent by the same 65 transmitting station and to beat the received signal to an intermediate frequency, said intermediate frequency being different for different ones of the receiving stations, means to combine and then rectify the intermediate frequency signals of all 70 receiving stations and means responsive to the energy so combined and rectified.

11. In a radio signaling system, the combination of a plurality of receiving stations having means to receive signal waves of the same fre- 75

- quency, means for supplying combining oscillations to all receiving stations, said combining oscillations being different for different ones of the receiving stations to produce with the received signal waves at the receiving stations intermediate frequency waves of different frequencies, means to add the intermediate frequency waves from all of the stations to produce a resultant wave, and means to detect the signal component of the said resultant wave.
12. A multiple station radio receiving system comprising a plurality of separated radio receiv-

ing stations, antenna means at each separated station for collecting from the ether a signal modulated wave of high frequency, means at each of said separated stations for producing, from said signal-modulated wave of high frequency, signal-modulated waves of intermediate frequency which are different for each station, and a single device for detecting the signal component of said waves.
